ATTORNEY

UNITED STATES PATENT OFFICE.

LOUIS A. BREITINGER, OF PHILADELPHIA, PENNSYLVANIA.

DESIGN FOR A CLOCK AND HALL STAND.

40,921.

Specification for Design. Patented Sept. 27, 1910.

Application filed June 23, 1910. Serial No. 568,601. Term of patent 3½ years.

To all whom it may concern:

Be it known that I, LOUIS A. BREITINGER, a citizen of the United States, and resident of the city and county of Philadelphia, State of Pennsylvania, have invented a new, original, and ornamental Design for Clock and Hall Stands, of which the following is a specification, reference being had to the accompanying drawing, forming part thereof.

The figure is a perspective view of a clock and hall stand, showing my new design.

I claim:

The ornamental design for a clock and hall stand, as shown.

LOUIS A. BREITINGER.
